UNITED STATES PATENT OFFICE.

GEORGE H. LANGEHENNIG, OF GUTHRIE, OKLAHOMA.

POST.

1,175,458.

Specification of Letters Patent. Patented Mar. 14, 1916.

Application filed May 6, 1913. Serial No. 765,856.

To all whom it may concern:

Be it known that I, GEORGE H. LANGEHENNIG, citizen of the United States, residing at Guthrie, in the county of Logan and State of Oklahoma, have invented certain new and useful Improvements in Posts, of which the following is a specification.

This invention relates to improvements in posts, such as fence posts, telegraph posts, trolley wire posts, and the like, and has for one of its objects to improve the construction and increase the efficiency and utility of devices of this character.

Another object of the invention is to provide a simply constructed post which may be readily adapted without material structural change for use in connection with posts as now in common use, and by means of which attachments, such as the rail portions of a fence, may be readily attached to and detached from the post structure without removing it from the ground.

Another object of the invention is to provide a post particularly adapted for use at the corners and angles of fences.

With these and other objects in view the invention consists in certain novel features of construction as hereinafter shown and described and then specifically pointed out in the claim.

As before stated the improved device may be employed in various localities and for various purposes, and it is not desired to limit the invention in this respect, but for the purpose of illustration the improved post is shown employed as a fence post, and in the drawings illustrative of the preferred embodiment of the invention, Figure 1 is a perspective view showing a pair of my improved posts arranged at a fence corner. Fig. 2 is a side elevation of one of the posts illustrating the manner of "setting" the same.

Corresponding and like parts are referred to in the following description and indicated in all the views of the drawings by the same reference characters.

The improved post comprises a body member 10 of any suitable material, but preferably of plate metal and extended at right angles to the body at the upper end, as shown at 11, and likewise extended at right angles intermediate the ends, as shown at 12, and with a portion below the extension 12 reduced in diameter and preferably rounded, as represented at 13, and reduced

intermediate the rounded portion, as represented at 14. The extension 13 is designed to be embedded in a mass of concrete, indicated at 15, with the extension 12 substantially even with the upper side of the concrete block. Rising from the extension 12 is a projection 16 of less width than the member 10 and provided with a transverse perforation to receive a pintle 17, the block 16 and its pintle forming a hinge member, as shown. Mounted to swing upon the pintle 17 is a member 18, preferably of plate metal, and corresponding in size to the member 10. The member 18 when in its upper position bears at its upper end beneath the outer end of the lateral extension 11 of the member 10, as shown in Figs. 1 and 2. The members 10-18 thus extend in parallel relation and are spaced apart a relatively slight distance, as shown. Clamp bolts 20 extend through the members 10-18 and thus hold them in spaced relations. Combined spacing and strand wire supporting blocks 21 are disposed between the members 10-18 and spaced to correspond to the strand wires 19 and upon which the latter are supported. The blocks thus form supports for all of the strand wires, except where the bolts 20 are located, and at these points the blocks are not employed but the strand wires next to the bolts are supported thereby. The blocks 21 are located upon the member 10 only and are thus independent of the member 18 as illustrated in Fig. 2.

When the improved post is to be erected a hole is formed in the ground to receive the cement which is to form the block 15 and the nuts of the bolts 20 released and the member 18 turned outwardly and the projection 13 embedded in the plastic cement, the outer end of the member 18 resting upon the ground and secured in position by a spike or other securing device 22 driven therethrough and into the ground, the member 18 thus serving as a temporary brace to support the member 10 until the cement has become hardened or "set". The member 18 is then released and turned into vertical position and secured in place by the clamp bolts. When the posts are finally set in position the strand wires 19 are arranged in the posts and the fence thus completed. In event of the impairment of the wires 19 they can readily be replaced by perfect wires without disturbing the posts.

When the posts are to be erected at the

corners of a fence, two of the posts are arranged at right angles to each other, as shown in Fig. 1, and the projections 13 disposed in a single block of concrete. The 5 adjoining members 10 are then united by metal L clamp members 23 which are bolted or otherwise secured to the post members.

The improved device is simple in construction, can be inexpensively manufactured, is strong, durable, and may be readily removed from place to place as required.

Having thus described the invention what is claimed as new is.

A post including a body portion having substantially flat side faces and provided at one extremity with a base extending laterally upon one side of the body portion, an overhanging terminal formed on the opposite extremity of the body portion and extending laterally therefrom in a direction with said base, a plurality of longitudinally spaced strand wire supporting blocks formed on one side of the body portion and extending laterally therefrom in a direction with

the base, and upstanding hinge lug formed 25 on the outer extremity of the laterally directed portion of the base, a substantially flat clamping member bifurcated at one extremity to receive said lug and swingingly connected thereto, the clamping member being movable to abut the free ends of the supporting blocks with the free extremity of the said member fitting beneath the overhanging terminal of the body portion, the body portion, the overhanging terminal 35 thereof, and the said clamping member occupying a space equal in width to the major width of the base and being disposed within the lines of the base, and a plurality of bolts providing strand supports detachably holding the clamping member in engagement with the said blocks. 40

In testimony whereof I affix my signature in presence of two witnesses.

GEORGE H. LANGEHENNIG. [L. s.]
